UNITED STATES PATENT OFFICE

ENOCH KARRER, OF AKRON, OHIO

ELECTRIC SWITCH

Application filed May 16, 1929. Serial No. 363,483.

This invention relates to electric switches, and particularly to multiple switches which control a plurality of circuits.

The object of the invention is to provide an improved switch of this type in which a single operating device is used to control all circuits, said device having a constant neutral position in which it lies at all times except when moved therefrom to open or close one of the branch circuits, and which device is mounted to have movements of different kinds for different purposes, as will more fully appear.

A further object of the invention is to provide a switch of this kind in which the operating device is arranged so that it may be used selectively to close and leave closed any one or more of a plurality of branch circuits, such devices being also usable to open said circuits.

A further object of the invention is to provide a multiple switch with an operating or controlling device for individually closing any one or more of a plurality of circuits and in any desired order, and which may also be utilized to simultaneously open all of the circuits which have been closed.

In the drawing, which represents one suitable embodiment of the invention, Fig. 1 is a plan view; Fig. 2 is a sectional elevation on the line 2—2, Fig. 1; Fig. 3 is a sectional plan view on the line 3—3, Fig. 2; and Fig. 4 is a detail view corresponding to Fig. 2 and illustrating a modification.

The switch forming the subject matter of the present invention may be made in various forms and styles. The arrangement shown for purposes of illustration in the drawing comprises a suitable enclosing casing including a base 1 designed for attachment to a suitable support and which, if made of conducting material, forms one common lead for all of the branch circuits, for which purpose it is provided with a suitable binding post 2 for the current lead 3. Upon the base 1 is a shell or jacket 4 having its top provided with an extension 5, the top and extension being provided with radial slots 6, one for each of the branch circuit switch devices to be operated.

Each branch circuit includes its own switch device, and as they are all alike, description of one will suffice for all. The switching devices may be of any suitable construction, such as single pole double throw when it is intended to have each switching device control two circuits, but, as illustrated for convenience, the switching devices are of the single pole single throw variety. They are shown as normally open but obviously might be of the normally closed variety. Each branch circuit includes a contact 7, shown as a pair of spring blades, mounted upon a binding post 8 to which one of the branch wires 9, 10, etc., is connected. Co-operating with the blades 7 is a switch blade 11 pivoted at 12 upon a U-shaped post 13 mounted on the base 1. Each switch blade includes three arms, the arm 11a being adapted to move into conducting position between the blades 7, an arm 11b which works in a slot in the post 13, and an operating arm 11c. Within the post 13 is a small wire spring 14 fixed at its lower end and having its upper end free and engaging in the angle of the switch blade between its arms 11a and 11b. This spring has a preponderating tendency to move the switch blade to open position, as shown at the right in Fig. 2, and when the switch is closed, as at the left in Fig. 2, the spring is slightly beyond dead center with a slight switch closing effect. The four operating arms 11c are all arranged to move in radial paths just beneath the slots 6.

The present switch mechanism is provided with a single operating device capable of manipulation by the operator and mounted to have a variety of motions, even as many as three different kinds of motions, for operating the several switch devices in different ways. Said operating device is usually arranged to have a plurality of motions of one kind for operating the switches in one direction and a single motion of another kind to operate the switches in the other direction. For example, the operating device may be in the form of a rod which may be tilted in various directions with different motions of the same kind to individually operate the 100

switches in one direction and may then have either or both of longitudinal and rotary motion for operating the switches in the other direction, either simultaneously as a group or in any predetermined or defined order, as will more fully appear. In the particular arrangement shown for purposes of illustration, and not in any sense of limitation, the operating device is provided with tilting motion in several directions for the one purpose and with longitudinal motion for the other purpose.

At their upper ends the arms 11c are provided with lateral projections 11d which lie adjacent to the operating device or rod 15 which in normal position lies vertically along the central axis of the casing. Said rod may be made of or cased with insulating material and is provided at its upper end, outside of the shell 4, with an operating finger knob 16. At its lower end it is suitably attached to the upper end of a short coiled spring 17, the lower end of which is beaded or otherwise secured to a stem 18 sliding in a sleeve 19 attached to the base 1, the stem 18 being normally held in its upper position by a compression spring 20.

The foregoing arrangement enables the knob 16 to be operated, in the form shown, by five movements. It can be swung or tilted radially outwardly through any one of the four slots 6, to the position shown at the left in dotted lines, Fig. 2. Such motion of the rod 15 moves outwardly the corresponding switch blade 11, by the engagement of rod 16 with its lateral shoulder 11d, and closes the particular branch switch. By such operations any one or more of the four branch circuits may be operated at will. They also may be operated in any order, and if this operation is a closing operation, as shown, then when closed they will remain closed until purposely opened. Upon release of the operating knob 16 it immediately moves back to its central axial neutral position, in which it lies at all times, so that the operator can depend upon its location even in the dark, and knows that it is actually ready for movement in any direction to operate a switch.

Depression of the knob 16 and consequent motion of the rod 5 and its attached parts longitudinally of the rod axis is also utilized for switch operating purposes,—for opening in the form shown,—to which end the stem 18 is provided with a collar 21 lying over the tail arms 11b of the switch levers. When any switch has been closed, as at the left in Fig. 2, its arm 11b lies beneath the collar 21. Consequently if the button 16 is depressed, the collar 21 moves down with it and engages the arms 11b of all switch levers which have been closed and opens said switches, which thereupon fly to the fully open position under the influence of the springs 14.

In the arrangement shown in Fig. 2, the

several switch levers are identical and the collar 21 is of annular washer form. Consequently it simultaneously engages and operates the tail arms of all of the switch devices which have previously been closed. However, simultaneous operation is not essential and in the form shown in Fig. 4 it will be understood that the several tail arms 11b of the switches are substantially alike or even identical, but the collar 21 is of optional form with projections or lugs 21a, 21b and 21c of different height, and these lugs are the parts which directly engage the tail arms 11b. As a result, operation of the switch operating device in Fig. 4 by longitudinal or axial motion to depress the collar 21 does not simultaneously open the several switches, but opens them in any desired pre-determined or definite order, according to the form and arrangement of the lugs.

In this switch, therefore, the closed casing presents to view merely an operating rod and button at its top. Motion of said button in any of the several radial directions closes the appropriate branch circuit and the button immediately flies back to central position, in which it may be depressed to open all circuits which have been closed. This device is therefore suitable for many uses, such as in automobile lighting control systems, and in places where the switch mechanism may be located in the dark, etc. Other advantages of the invention will be apparent to those skilled in the art.

Having described my invention, I claim:

1. Switch mechanism of the class described, comprising a plurality of switch structures embodying switch parts movable into or out of contacting relation with each other to close or open a circuit and a single operating means therefor, said operating means being tiltable to selectively and individually move any one of said switch structures into operative position without affecting the position of any of the other switch structures and being slidably movable to simultaneously render all of said switch structures inoperative after they have been placed in operative position, and yieldable means for returning said operating means to its original position.

2. Switch mechanism of the class described, comprising a support, a plurality of switch structures mounted thereon, and a single operating means mounted for selective movement in a plurality of directions to individually actuate any one of said switch structures, said single operating means being likewise mounted for movement in one direction uniformly to all of said switch structures to simultaneously actuate a plurality thereof.

3. Switch mechanism of the class described, comprising a support, a plurality of switch structures mounted thereon, a single

operating means mounted for selective tilting movement in a plurality of directions to individually actuate any one of said switch structures, said single operating means being 5 likewise mounted for sliding movement in a direction uniform to all of said switch structures to simultaneously operate a plurality thereof.

4. Switch mechanism of the class described, comprising a support, a plurality of switch structures mounted thereon, a single operating means mounted for selective tilting movement in a plurality of directions to individually actuate any one of said 10 switch structures, said single operating means being likewise mounted for sliding movement in a direction uniform to all of said switch structures to simultaneously operate a plurality thereof, and yieldable 15 means for resisting movement of said single operating means and returning said single operating means to its normal unoperated position after operation thereof.

20 In testimony whereof I hereby affix my
25 signature.

ENOCH KARRER.
